H. G. WEBSTER.
SIGNALING SYSTEM.
APPLICATION FILED JULY 5, 1906.

921,319.

Patented May 11, 1909.

UNITED STATES PATENT OFFICE

HARRY G. WEBSTER, OF CHICAGO, ILLINOIS, ASSIGNOR TO MILO G. KELLOGG, OF CHICAGO, ILLINOIS.

SIGNALING SYSTEM.

No. 921,319.

Specification of Letters Patent.

Patented May 11, 1909.

Application filed July 5, 1906. Serial No. 324,842.

To all whom it may concern:

Be it known that I, HARRY G. WEBSTER, a citizen of the United States, and a resident of the city of Chicago, county of Cook, and State of Illinois, have invented certain new and useful Improvements in Signaling Systems, of which the following is a specification.

This invention relates to signaling systems in which electric signaling currents, set up in any of a plurality of individual transmitting circuits, serve to cause the actuation of a signal-receiving device common to all of the transmitting circuits.

15 The object of the invention is to provide improved means whereby abnormal conditions in any of the transmitting circuits, such as the interruption or grounding of the wires thereof, will cause the operation of 20 mechanism serving to isolate the circuit which is in trouble from the receiving device and thus prevent interference with signals transmitted over circuits which are not in trouble.

25 The invention particularly relates to circuits in which the signaling currents are caused by a momentary closure of a circuit including a source of current and a relay or other electromagnetic device, which latter 30 device serves to control the circuit of a telegraphic register or other signal-receiving mechanism.

In accordance with a preferred form of 35 my invention, I associate with each transmitting circuit a so-called double-acting relay having two windings, one winding being included in the individual transmitting circuit and being of relatively low energizing capacity, and the other winding being 40 of relatively high energizing capacity and included in a local circuit. The double-acting relay is provided with contacts normally controlling the circuit of a signal-receiving device and controlling also the circuit 45 of a slow-acting relay or equivalent device also common to the plurality of transmitting circuits. The double-acting relay is also provided with contacts which act in conjunction with contacts of the slow-acting 50 relay to control a circuit of the local winding of the double-acting relay. The momentary closing or opening of the circuit in the normal transmission of signals serves to cause the operation of the signal-receiving 55 device in the well-known manner; but when

an accidental opening or grounding of an individual circuit for more than the normal duration occurs, the complete actuation of the common slow-acting relay brings into circuit the local winding of the double-acting relay associated with said individual circuit, causing a further actuation of the contacts of the double-acting relay. This complete actuation interrupts the circuit of the slow-acting relay and receiving device, 60 and closes a locking circuit through the local winding which also includes a visual signal associated with the double-acting relay and allows the slow-acting relay and receiving device to assume their normal positions in readiness for another operation. The display of the visual signal serves to call the attention of an attendant to the fact that the individual circuit is in trouble, 65 and the double-acting relay is restored to its 70 normal position manually when the trouble has been remedied.

The invention will be more fully understood from the accompanying drawing, in which—

Figure 1 illustrates its embodiment in a structure in which the individual transmitting circuits consist of the subscriber's lines of a telephone exchange system such as is described in United States Patent #647,583, 80 dated April 17, 1900, these telephone lines having the signaling function, as for fire alarm or other use, in addition to their ordinary telephonic function. In this figure, I have diagrammatically illustrated the system as one in which the receiving device or register is included in a normally open local circuit. Fig. 2 illustrates diagrammatically a similar arrangement in which the receiving device is in a normally closed circuit.

Like characters refer to corresponding parts in the two figures.

Referring to Fig. 1, circuits A, A' and A² indicate telephone lines extending from the central office to substations and to signal-transmitting stations, the substation and signal-transmitting devices being indicated only in connection with line A and having the usual transmitter t, receiver r, switch-hook h, condenser c and call-bell b. The several lines include, at any convenient point, the windings or relays B, B' and B², which windings are indicated as "twin" windings and differentially connected and therefore do not alter the energization of the

relay magnet during the telephonic operations of the structure. The subscriber calls in the usual manner by closing the circuit of the line limbs 1 and 2 through his receiver 5 and transmitter, thus allowing current to flow from battery C, through the line relay 14, the winding 4 of the relay B, line limb 1 the substation, line limb 2, winding 5 of relay B to the return side of the battery. 10 This current serves to energize relay 14, causing the illumination of the telephone line signal lamp 16; and upon the insertion of a connecting plug, current is supplied to the line limbs through a repeating coil in 15 the cord circuit, and the relay 14 is disconnected by the operation of cut-off relay 17, as fully set forth in the above mentioned patent. The telephonic current, which flows through windings 4 and 5 of relay B 20 in opposite directions, does not energize the magnet of relay B. When the alarm or special signal is to be sent, the limb 1 of the line is intermittently connected to ground either by the manually operated key h, or by 25 the diagrammatically indicated call-box device D in which the depression and subsequent release of the lever h' causes contact wheel w to rotate and intermittently engage spring s. At each grounding of the line 30 limb, current of momentary duration will flow from battery C, through relay 14, winding 4 of relay B, and thence through limb 1 to ground and the return side of the battery. This current flow will cause a momentary attraction of armatures 7 and 11 35 of relay B. Armature 7 engages contact 8, but the relay is not at this time sufficiently energized to cause contact 8 to move out of engagement with contact 9. A circuit may 40 therefore be traced from battery C, through the winding of register R, the winding of a slow-acting relay 19 and through wire 33, contact 9, contact 8, armature 7, key 18 and wire 32 to the return side of the battery, 45 thus causing the register or corresponding device to give its indication. The relay 19 is illustrated as having its armature provided with a dash-pot 20 in order that it shall require a current flow of some considerable duration before the armature 21 will come into engagement with contact 22. It is to be understood that any other form of slow-acting relay may be used in the structure and that the current impulses are so 50 spaced as to prevent a sequence of impulses from causing a complete movement of the relay armature. The impulses, which are sent in the normal operation of signaling, are not of sufficient duration to cause the 55 engagement of the contact 22 and therefore, while armature 11 of relay B engages contact 12 at each current impulse, the wire 34, which connects armature 11 with contact 22, remains open and no further result occurs. 60 If, however, limb 1 of the line becomes 65 grounded for an abnormal length of time, the circuit previously traced through register R and relay 19 will be maintained for a sufficient length of time to allow armature 21 of relay 19 to engage contact 22, at which 70 time a circuit may be traced as follows: from the active terminal of battery C, through wire 35, through winding 6 of relay B, through lamp 13, contact 12, armature 11, wire 34, contact 22 and armature 21 to 75 the return side of the battery. The current flowing through this circuit is sufficient to cause a greater energization of relay B and the complete actuation of its contacts, causing contact 8 to disengage contact 9 and to 80 engage contact 10. The disengagement of contact 9 interrupts the circuit of the register and relay 19, and the engagement with contact 10 closes a locking circuit for relay B which may be traced as follows: from the 85 active terminal of battery C, through wire 35, winding 6, lamp 13, contacts 10, 8 and 7, key 18, and wire 32 to the return side of the battery. This current serves to maintain the complete attraction of the armatures of 90 relay B and to cause the illumination of the lamp 13, and the register R and relay 19 have assumed their normal positions in readiness for a subsequent operation. The illumination of lamp 13 indicates to the attendant that the line associated with that lamp is in trouble, who, when the trouble has been remedied, interrupts the locking circuit just traced by depressing the key 18, thus allowing the relay contacts to assume their normal positions. It will be obvious, therefore, 95 that if line A be in trouble, signals may be received from line A' or A'', or vice versa, without interference from such trouble. 100

Fig. 2 illustrates diagrammatically a modification of the structure of Fig. 1, in that the register R' and magnet 19 are included in a normally closed circuit, which may be traced from the upper terminal of battery C, through the magnet winding of register 110 R', the winding of magnet 19, and thence through wire 36, contact 28 and armature 27 of relay B', contact 28 and armature 27 of relay B', and contact 28 and armature 27 of relay B, to the return side of the battery 115 through wire 37. The current, which flows through this circuit normally, holds the armature of the register out of engagement with the tape-wheel and the armature of relay 19 out of engagement with its contact 31. 120 If a signal be sent over line A, the consequent energization of relay B causes armature 27 to engage contact 29 and armature 23 to engage contact 25, but is insufficient to cause a further actuation of the armature. 125 The actuation of armature 27 at this time interrupts the circuit of the register and relay 19 in the pre-determined manner, thus causing proper signals to be made. The interruptions, however, are of such short du- 130

ration that armature 21 does not engage contact 31, and consequently no current flow results from the engagement of armature 23 with contact 25. If, however, through the 5 accidental grounding of limb 1 of line A, the relay B be energized for more than the normal duration, armature 21 of relay 19 will engage its contact 31 during the time that armature 23 of relay B engages its contact 25, and current will flow over the circuit which may be traced from the upper terminal of battery C, through wire 40, key 18, lamp 13, winding 6 of relay B, armature 23, contact 25, contact 24, wire 38, contact 31, 15 and armature 21 to the return side of the battery. This current causes an increased energization of the magnet of relay B and a complete attraction of its armatures. The complete actuation of armature 27 again 20 closes the circuit of register R' and relay 19 at contacts 30, 29 and 27, thus placing them in readiness for operation by currents on line A' or A². The complete actuation of armature 23 causes contact 25 to engage contact 25 25 and subsequently break contact 24, and this operation completes a locking circuit including the signal lamp 13, which may be traced from the upper terminal of battery C, through wire 40, key 18, lamp 13, winding 6, armature 23, contact 25, contact 26, 30 and wire 39 to the opposite side of the battery, thus maintaining the attraction of the relay armatures and the display of the signal until the circuit is interrupted by the attendant as in Fig. 1.

While I have illustrated my invention as embodied in a combined telephone and alarm signaling system, I do not wish to be limited to this particular embodiment, as it is obvious that it may be used in connection with many other signaling structures. While the relays B, B', B² are diagrammatically illustrated as having two armatures, it is evident that any so-called "double-acting" relay may 45 be used, in which the contacts controlled by the relay magnet have two operative positions other than the normal one. Likewise lamp 13 or the register R may be replaced by any preferred signaling mechanisms, and 50 also that various other ways of supplying current to the various circuits may be used, other than that of having one common source. I therefore do not wish to be limited to the structure illustrated and described, but aim to cover any variations or 55 modifications of the invention by the following claims:

1. A signaling system comprising a plurality of transmitting circuits, a local transmitting apparatus connected to each circuit, a relay in each circuit, a signal-receiving circuit which is controlled by any of the relays, a source of electricity, a switch operated by any of the relays whenever there

is more than the normal momentary operation of the relay, to complete a circuit cutting off the control of the receiving circuit by the relay, and signal-receiving apparatus in the receiving circuit. 65

2. A signaling system comprising a plurality of transmitting circuits, a local transmitting apparatus connected to each circuit, a relay in each circuit, a signal-receiving circuit which is controlled by any of the relays, a source of electricity, a switch operated by any of the relays whenever there is more than the normal momentary operation of the relay, to complete a circuit cutting off the control of the receiving circuit by the relay, a signal associated with the 70 relay adapted to be displayed when the control is cut off, and signal-receiving apparatus in the receiving circuit. 75

3. A signaling system comprising a plurality of transmitting circuits, a local transmitting apparatus connected to each circuit, a relay in each circuit, a signal-receiving circuit which is controlled by any of the relays, a source of electricity, a slow-acting switch operated by any of the relays whenever there is more than the normal momentary operation of the relay, to complete a circuit cutting off the control of the receiving circuit by the relay, a signal associated with the 80 relay adapted to be displayed when the control is cut off, and signal-receiving apparatus in the receiving circuit. 85

4. A signaling system comprising a plurality of transmitting circuits, a local transmitting apparatus connected to each circuit, 100 a relay in each circuit provided with a local winding, a signal-receiving circuit which is controlled by any of the relays, a source of electricity, a common switch operating in conjunction with any of the relays whenever there is more than the normal momentary operation of the relay, to complete a circuit through the local winding of the relay, switching mechanism responsive to the energization of said local winding to cut off 105 the control of the signal-receiving circuit by the relay, and signal-receiving apparatus included in the signal-receiving circuit. 110

5. A signaling system comprising a plurality of transmitting circuits, a local transmitting apparatus connected to each circuit, a relay in each circuit provided with a local winding, a signal-receiving circuit which is controlled by any of the relays, a source of electricity, a common switch operating 115 in conjunction with any of the relays whenever there is more than the normal momentary operation of the relay, to complete a circuit through the local winding of the relay, switching mechanism responsive to the 120 energization of said local winding to cut off the control of the signal-receiving circuit by the relay, an indicator adapted to be dis- 125

played by current flowing through the local winding, and signal-receiving apparatus included in the signal-receiving circuit.

6. A signaling system comprising a plurality of transmitting circuits, a local transmitting apparatus connected to each circuit, a relay in each circuit provided with a local winding, a signal-receiving circuit which is controlled by any of the relays, a source of electricity, a common switch controlled by any of the relays whenever there is more than the normal momentary operation of the relay, to complete a circuit through the local winding of the relay, switching mechanism responsive to the energization of said local winding to cut off the control of the signal-receiving circuit and the common switch by the relay, and signal-receiving apparatus included in the signal-receiving circuit.

7. A signaling system comprising a plurality of transmitting circuits, a local transmitting apparatus connected to each circuit, a relay in each circuit provided with a local winding, a signal-receiving circuit which is controlled by any of the relays, a source of electricity, a slow-acting relay in the signal-receiving circuit operated by any of the relays whenever there is more than the normal momentary operation of the relay, to complete a circuit through the local winding of the relay, switching mechanism re-

sponsive to the energization of said local winding to cut off the control of the signal-receiving circuit by the relay, and signal-receiving apparatus included in the signal- 35 receiving circuit.

8. A signaling system comprising a plurality of transmitting circuits, a local transmitting apparatus connected to each circuit, a relay in each circuit provided with a local 40 winding, a signal-receiving circuit which is controlled by any of the relays, a source of electricity, a slow-acting relay in the signal-receiving circuit operated by any of the relays whenever there is more than the 45 normal momentary operation of the relay, to complete a circuit through the local winding of the relay, switching mechanism responsive to the energization of said local winding to cut off the control of the signal-receiving circuit by the relay, an indicator 50 adapted to be displayed by a current flowing through the local winding, and signal-receiving apparatus included in the signal-receiving circuit. 55

In witness whereof, I hereunto subscribe my name this 30th day of June 1906.
